DESIGN FOR A POPCORN DISPENSING CABINET OR SIMILAR ARTICLE

Harvey C. Wheeler, Miami Beach, Fla.

Application June 11, 1941, Serial No. 101,400

Term of patent 7 years

To all whom it may concern:

Be it known that I, Harvey C. Wheeler, a citizen of the Principality of Monaco, residing at Miami Beach, in the county of Dade, in the State of Florida, have invented a new, original, and ornamental Design for a Popcorn Dispensing Cabinet or Similar Article, of which the following is a specification, reference being had to the accompanying drawing, forming a part thereof.

I claim:

The ornamental design for a popcorn dispensing cabinet or similar article, substantially as shown.

HARVEY C. WHEELER.
